KNITTING MACHINE

Frank J. Ford, Worcester, Mass., assignor of one-third to Harry Whittaker, Oxford, and one-third to Max B. Striar, Worcester, Mass.

Application May 25, 1943, Serial No. 488,371

3 Claims. (Cl. 66—135)

1

This invention relates to improvements in knitting machines and methods of knitting.

Objects of the invention include the provision of a knitting machine having a single row of needles to which weft threads are fed at intervals, one weft thread being introduced to the needles in series between each rise thereof, in combination with a series of jacks guiding warp threads to be knit into a fabric with the weft threads, said fabric thereby including weft and warp threads knit in loops, wherein said jacks are provided with means to reciprocate the same in a direction transverse to the needles and the needle motion, to shift the warp threads from one needle to the next adjacent needle and then to shift the jacks back to the original needle, whereby double offset or right and left loops are formed in each wale together with the chain loops of the wefts.

Further objects of the invention include the provision of novel power transmissions for a pair of jack cam rings and for the needle cam ring; the provision of novel warp guiding jacks; the provision of a novel slide mechanism for reciprocating the jacks; and the provision of a new and useful method of knitting.

Other objects and advantages of the invention will appear hereinafter.

Reference is to be had to the accompanying drawings in which

Fig. 1 is a view in elevation of a cylinder knitting machine embodying my invention;

Fig. 2 is an enlarged detail view of the support and drive for the weft bobbin ring;

Fig. 3 is a sectional detail view of the drive for the needle cam ring;

Fig. 4 is an elevational detail view of the drive for the jack cam rings;

Fig. 5 is a section on line 5—5 of Fig. 4;

Fig. 6 is a section showing the needle cam ring;

Fig. 7 is a still further enlarged view of the jack reciprocating mechanism;

Fig. 8 is a sectional view of the jack and slide support;

Fig. 9 is a top plan view of the slide support, looking in the direction of arrow 9 in Fig. 7;

Fig. 10 is a section on line 10—10 of Fig. 8;

Fig. 11 is a section on line 11—11 of Fig. 7;

Fig. 12 is a plan view of a jack; and

Figs. 13 to 17, inclusive, are diagrammatic views illustrating the action of the warp jacks with relation to the needles.

The present invention is illustrated in the drawings as applied to a cylindrical knitting machine, but it is to be understood that the invention is

2

equally applicable to other types of knitters, and I do not wish to be limited to the constructions shown except as recited in the appended claims.

The knitting machine here illustrated is supported on legs 10 or other base means, these legs supporting a frame or the like 12 and bracket 14. The latter journals a shaft 16 having fast and loose pulleys 18, 20, driven by a belt or the like 21 and shaft 16 extends under the edge of frame 12 and is also journaled therein or in a supporting leg as at 22. Shaft 16 is provided with a bevel gear 24 intermediate its length and another bevel gear 26 at its inner end, for the purpose of driving various cam rings, as will be explained.

5 A bracket 28 is mounted on frame 12, adjacent but above shaft 16, by means of a leg 30. This leg provides a journal for a vertical shaft 32 which is also journaled in a sleeve 34 forming a part of the bracket. Shaft 32 has a gear 36 fixed thereto 10 in mesh with the intermediate gear 24 on shaft 16, and at its other end shaft 32 mounts a gear 38 in mesh with a gear 40 on a stud shaft 42, the latter being mounted in bracket 23 and a vertical arm 44 thereof. A spur gear 46 is fast to the stud 15 shaft 42 and is rotated therewith from belt 21 as above described.

20 Bobbins 48 are mounted on spindles on a large bobbin ring 50, these bobbins providing the weft or cross threads in the fabric to be manufactured. The bobbin ring is toothed on its under side to mesh with the spur gear 46 and is thus rotated, carrying with it the bobbins, each of which unwinds as suitable guides not shown, lead the threads to the needles. The bobbin ring is arranged to ride on a supporting roller 52 mounted at the top of the bracket.

25 Diametrically across the bobbin ring from the mechanism just described, the construction is repeated in reverse, see Fig. 1. Roller 54 supports the bobbin ring which drives spur gear 56 mounted on bracket 57. In turn, spur gear 56 drives gears 58, 60, shaft 62, gear 64, and a shaft 66 is thereby driven from shaft 16, which is here aligned therewith. A hand wheel 68 is provided 30 on shaft 66 but obviously this shaft can be power driven also if desired. By this means the bobbin ring is balanced and rotates easily, any desired means, such as a center shaft being used to maintain the ring in central position. Whether shaft 66 is driven directly or by the bobbin ring, it is provided with a gear 70 similar to gear 26 on shaft 16.

35 Fig. 3 shows the purpose of gears 26 and 70, although only the latter is disclosed in relation to the needle cam ring 72. The cam ring is

toothed to mesh with gears 26 and 70 and is driven thereby in timed relation to the bobbin ring. A cam is shown at 74, the cam slot at 76, and the needles 78 are reciprocably mounted in needle slots in the cylinder 80 as usual, and rise and fall in accordance with the speed of rotation of shafts 16 and 66.

Brackets 82 are supported on frame 12 and in turn mount a large fixed cylinder 84 the axis of which coincides with the axis of rotation of the bobbin ring and needle cam ring. This fixed cylinder is vertically slotted at close intervals on its interior, as at 86, see Figs. 7, 8 and 9. Further brackets 93 conveniently placed on frame 12 support an interior fixed cylinder 90 exteriorly slotted as at 92 correspondingly to slots 86. Cylinders 84 and 90 are concentric and radially spaced, so that each slot 86 faces a slot 92. Inner cylinder 90 is divided at 94 for a purpose to be described. Brackets 88 rotatively support the lower jack guide cam ring to be described.

Warp threads 96 are guided to the needles by jacks 98, the threads unwinding from fixed bobbins not shown but coming into the machine through eyes in a guide ring 100 in a manner similar to that disclosed in my Patent No. 2,289,492, issued July 14, 1942, reference being had to guide ring element 66 therein. Jacks 98 are novel per se, but the principal novelty resides in the motion imparted thereto by sliding jack guides 102.

Jack cams or guides 102 are all similar and each comprises a central flat body 104 which is inclined with relation to end pieces 106, the latter being parallel but offset due to the inclined central body 104. In the end pieces adjacent the junctions with the body 104 there are provided pairs of tabs 108, 110, which extend outwardly forming guiding means fitting slots 89 and 92, it being observed that the upper tabs 108 are located in slots two removed from the slots containing lower tabs 110, see Figs. 7 and 9.

Each jack 98 comprises spaced side plates having spacers 112 securing the plate together in the correct relation. The jacks are assembled one to each jack guide, the latter being contained between two spacers, see Fig. 10, and the jack itself is located between the pairs of tabs 108, 110. The shanks of the jacks extend inwardly radially of the cylinders projecting through the inner cylinder at the space 94, and terminating in the downturned fingers 114 containing guide eyes 116 to guide the warp 96 to the needles.

It will be apparent from the above that the jacks 98 move laterally and the jack cam guides 102 move vertically. The jack guides, being reciprocated vertically in the slots in the fixed cylinders 84, 90, will reciprocate the jacks laterally due to the inclined central bodies 104 which thereby act as cams for this purpose, and therefore each warp thread will be thus passed back and forth between a pair of needles. This motion of the jacks thus provides a double offset loop or right and left loops in each warp in adjacent courses and partially forming two wales with each warp.

To vertically reciprocate the jack cam guides I provide a pair of jack guide cam rings which rotate about an axis coinciding with that of the needle cam ring. Upper cams 118 are mounted to depend from the upper cam ring 120 which is suspended at diametrically opposite points on rollers 122 journaled on brackets 124, the latter being mounted on brackets 44 and 58. Upper cams 118 are provided with inclined surfaces

5 to depress the jack guides, while lower cams 126 are shaped to raise the guides. The lower guides are mounted on a lower cam ring 128 and alternate with the upper cams in a vertical direction, see Figs. 1 and 7. The lower cams may be provided with rearward extensions 130 to prevent dropping of the guides.

Both upper and lower guide cam rings are toothed on their outer peripheries, as shown, to 10 mesh with spur gears 132, 134 respectively, both of which are fast to a single shaft 136 journaled in bracket arms 138 on support 140. Another ring 142, also toothed, is mounted on a series of 15 brackets 144, bolted to the needle cam ring 72 to rotate therewith, so that the ring 142 is positively driven. A third gear 146 on shaft 136 meshes with the teeth on ring 142 to drive jack guide cam rings 120, 128 at the same speed. Gears 132 and 134 are flanged to aid in supporting the 20 guide cam rings.

Gears 26 and 70 rotate the needle cam ring, ring 142, shaft 136, and the upper and lower cam rings 120, 128, thus vertically reciprocating the 25 guides 102 and thereby laterally reciprocating the jacks 98.

30 The needle action is conventional and it is thought that the needle cams need not be further illustrated. These cams reciprocate the needles in the usual manner, and the needles are raised and lowered one cycle for each shift of the jacks. Thus, the needles being fed, the jacks operatively associated therewith are shifted, say to the left, to bring the warp threads to certain needles, whereupon the needles continue their feeding 35 movement to form the conventional loops in the wefts and the warp loops. On the next needle feed, the jacks are shifted again to original position and the needles again operate, repeating the weft loops, but this time the warp loops are 40 formed on needles to the right of the needles forming the just prior warp loops, as respects each warp thread. This action is repeated to form the fabric with the double offset right and left warp loops in combination with the usual 45 weft loops. The shift of the jacks depends on the angle of inclination of the jack guide bodies above described, and the degree of shift determines the needles engaging the ways threads, so that by a variation in inclination of the jack cam 50 guides, a single warp thread may be alternated between adjacent needles, or between needles having a space therebetween, or between needles spaced by one or more needles. In brief, each 55 warp jack passes its thread from one to another needle and back again and repeat, and therefore a fabric having conventional loops, and interengaged double offset warp loops is provided. Figs. 13 to 17 inclusive show the action of the warp 60 jacks with relation to the needles. Fig. 13 illustrates a complete cycle and the needles are shown in a rising and falling movement as occasioned by the needle cams. Section A of Fig. 13 corresponds to Fig. 14 wherein the jacks are stationary and as to the left hand needle in Fig. 14 the 65 latch closes on the warp thread and the weft is cast off. The right hand needle casts off both the weft and the warp. Section B of Fig. 13 corresponds to Fig. 15 and shows the needles up and the jack moved to the right. The left hand needle has now formed a loop with the warp and the 70 right hand needle having previously cast off, receives the warp thread. In this position of the needles, the latches of course are open. Section 75 A¹ of Fig. 13 corresponds to Fig. 16 wherein the needles are down and the latches are closed, the

jack remaining in the same position as in Fig. 15. In this case the left hand needle casts off both weft and warp and the right hand needle latch closes on the warp and casts off the weft. Section B¹ of Fig. 13 corresponds to Fig. 17 wherein the needles are again up with the latches open, and the warp is fed to the left hand needle. Were the diagram to be continued to the right, section A of Fig. 13 and Fig. 14 would be repeated, etc.

I intend to knit a filler into the fabric for blanket cloth, overcoatings, and allied heavier goods, and I therefore provide guides for laying in such a filler in each course. These guides do not form a part of the present invention however, and in fact known devices of this character can be used, as disclosed in my above identified patent.

Reference is hereby made to my copending application S. N. 402,293, filed July 14, 1941, Patent No. 2,346,159, dated April 11, 1944, for illustration of the cloth knitted by the present machine.

Having thus described my invention and the advantages thereof, I do not wish to be limited to the details herein disclosed, otherwise than as set forth in the claims, but what I claim is:

1. A knitting machine comprising a needle cylinder, a needle cam ring, means to rotate the ring, a fixed cylinder, slots in the cylinder, jack

cams in the slots for reciprocable motion therein, further cams to reciprocate the jack cams, jacks mounted in the fixed cylinder for movement therein, said jack cams moving the jacks, and cam rings rotatable to reciprocate the jack cams, said last named cam rings having driving connections from the first named ring.

2. A warp knitting machine comprising a needle cylinder, a circular series of needles in said cylinder, and needle cam means operatively arranged therewith, warp thread guiding jacks movable circumferentially of the needle cylinder, means to reciprocate the jacks, said means comprising a cam for each jack, each jack cam being movable relative to its jack to effect the reciprocation thereof, and further cams for moving the jack cams.

3. A warp knitting machine comprising a sequence of needles in line, cam means for actuating the needles, warp jacks reciprocable transversely of the needles and parallel to the line of needles, jack cams operatively arranged relative to the jacks, said jack cams being reciprocable to impart the reciprocating movement to the jacks, and successive cams for reciprocating the jack cams.

FRANK J. FORD.
